UNITED STATES PATENT OFFICE.

NATHAN ALLEN GIBBONS, OF MARTINS FERRY, OHIO.

SHIPPING DRUM.

Application filed June 15, 1922. Serial No. 568,371.

To all whom it may concern:

Be it known that I, NATHAN ALLEN GIBBONS, a citizen of the United States of America, and resident of Martins Ferry, 5 county of Belmont, and State of Ohio, have invented certain new and useful Improvements in Shipping Drums, of which the following is a specification.

This invention relates broadly to metallic 10 receptacles, and more particularly to a shipping drum or can of knock-down form.

The primary object of the invention is to provide a relatively inexpensive construction of drum designed as a container for 15 asphaltum, caustic soda, or other semi-liquid materials or substances which become solidified following introduction in the container.

Containers of the character referred to are ordinarily destroyed in effecting removal of 20 the solidified contents thereof; and, consequently, such containers need not possess the durability of containers which are to be re-used. Further, because of the nature of the materials to be contained thereby, 25 such containers need not have the close-fitting joints which are required in containers designed for holding liquids.

As previously stated, it is the chief aim 30 of the present invention to provide a cheap form of shipping drum adapted for the reception of contents of the character referred to. Further, it is an object to provide such a container which is adapted to be furnished to the packer or other user in 35 knocked-down form, thus providing for great economy in space both in shipping and storage prior to use, and which may be readily set up and closed by any unskilled person without the use of other than ordinary tools.

In describing the invention in detail, reference is made to the accompanying drawings, in which—

Figure 1 is a top plan view of the drum 45 showing the head partially secured in place;

Figure 2 is a view of the same partly in side elevation and partly in section;

Figure 3 is an end elevation of a plurality of body members occupying nested 50 relation; and—

Figure 4 is a sectional view of a drum illustrating a modification.

Referring to said drawings, 1 indicates the cylindrical drum body, which is made 55 of a single piece of sheet metal having opposite reversely turned hook-like edges 2

and 3 designed to be disposed in interlocked relation and to be flattened down upon each other in setting up the drum. In the open form shown in Fig. 3, said drum body is 60 adapted to be nested with similar bodies to economize shipping and storage space.

Each of the opposite ends of the body 1 is shaped to form reverse bends in which an inner downwardly extending member 4 seats 65 closely against said body and an upwardly extending member 5 stands parallel to said member 4 at a distance from the latter providing an intermediate channel 6. Said channel is designed for the reception of a 70 downturned peripheral flange 7 which is formed upon a circular head or closure 8 and which has relatively less width than the depth of said channel so that said head may seat directly upon the top of the bend 75 at the junction of the body with the member 4, as shown in Fig. 2.

The outer member 5 rises to a height considerably above the top of the bend above referred to and the terminal portion thereof is provided with a plurality of vertically extending slits 9 whereby it is divided 80 into relatively narrow tongues 10 which are adapted to be bent inward into closely overlying relation to the adjacent portion of the 85 head 8 for firmly retaining the latter in place.

In the modification shown in Fig. 4, the provision of reverse bends and the channel 6 is dispensed with. Somewhat differently 90 expressed, the body 1^a is retained in true cylindrical form from end to end, and tongues 10^a are formed in the end of said body by the provision of slots 9^a. Said tongues 10^a are turned inward and then 95 downward parallel to the cylinder walls to form an intermediate internal channel 6^a adapted for the reception of the peripheral flange 7^a of the head 8^a, said flange in this instance being outwardly directed and divided into tongues 11 through the provision of slits 12 spaced to correspond with the spacing of the slots 9^a. Following seating of said flange 7^a in said channel, the tongues 10^a and the tongues 11 are together bodily 100 turned inward, as shown at the right in Fig. 4, thus forming a fold of double-seam type whereby the head 8^a is firmly held in place.

As is manifest, the drum either constructed in the preferred form shown in 110 Figs. 1 and 2, or in the modified form shown in Fig. 4, may be readily set up and

closed by any person, using only a hammer for turning the tongues into head-retaining position.

What is claimed is:

- 5 1. A knock-down sheet-metal shipping drum comprising a cylinder body, an end of said body being reversely bent to form an inner downwardly extending member resting against the adjacent portion of the body
- 10 and an outer upwardly extending member located parallel to and at a spaced distance from said inner member whereby an intermediate channel is formed, said outer member extending above the level of the junction of said inner member with the body and being provided with vertical slits whereby terminal tongues are formed therein, and a head having a downturned peripheral flange for seating in said channel, said
- 15 tongues being adapted for bending inward into overlying seated relation to said head.
- 20 2. A knock-down shipping drum of the

character described comprising a cylindrical sheet-metal body having edges provided with means whereby they may be secured in interlocked relation, each end of said body being reversely bent to form inner and outer parallel members with an intermediate seating channel, a head-like closure for said body having a peripheral flange for seating in said channel, the outer of said parallel members being extended past the junction of said inner member with said body and being provided with slits whereby are formed tongues which are adapted to be bent inward into seated relation to said closure for retaining the latter in seated position.

In testimony whereof, I affix my signature in presence of two subscribing witnesses.

NATHAN ALLEN GIBBONS.
